PHOTOCOPY METER

This invention applies to photocopying apparatus and serves to meter and stop a moving sensitive strip at a given position with great accuracy. The strip stops momentarily for some particular treatment, then continues. This invention aligns successive advances at the treatment station, for example a strip of paper or film at a copying station precisely.

Need for exact positioning is readily apparent. To illustrate, if an inch space is intended to be left between exposures then an $\frac{1}{8}$ inch variance in stopping the film can mean over 12 percent error. This might well be cumulative. The problem is old, but suggested cures have not been satisfactory; overrun and underrun remain serious faults.

Difficulties are compounded when the apparatus must be adaptable to stop the strip at different distances. When different predetermined lengths are desired, the stopping mechanism must be versatile. In some cases the changes of advance may be in given multiples, as for example when a given set of advances is to be in multiples of a half inch, longer or shorter than previously. Or, the change may be extended to some multiple of other units, as change from half inch increments to some multiple of seven-eights inch. The stopping must still be accurate.

Objects of this invention are to meet various sources of error in an operating machine. Such are play and tolerances in moving parts, time delays and many sources of sluggish action. Another object is to maintain high and continued precision in stopping advances of a film strip at predetermined intervals. Other objects are to provide versatility and ease of adjustment in apparatus to change from one distance of advance to another and to change or adjust to meter strip of one quality or another. (It is clear that this apparatus does not depend on sprocketed film). Other objects and advantages of this invention will appear from the following detailed description of the preferred embodiment of this invention as shown in the attached drawing.

Novel features of this invention are set out in the accompanying claims.

The drawing shows a schematic arrangement of the combination of parts forming the preferred embodiment of this invention.

The drawing shows a strip 1 drawn by power of motor 2 from a supply roll 3 to accumulate on a takeup roll 4. Strip 1 travels over various positioning rolls. Such are illustrated as rolls 5 and 6 at the beginning of a flat path of travel of strip 1 and roll 7 nearer terminal roll 4. As means to meter advances of strip 1 and also to control stopping of the strip, roll 8 is placed at the end of the flat path of travel shown. Roll 7 is positioned to wrap strip 1 around a substantial at least semicircular arc of roll 8.

Motor 2 drives takeup roll 4, as illustrated by belt 9. Drive of metering roll 8 may include, to a greater or less extent, power through adjustable belt 10. However, metering roll 8 may be rotated sufficiently by the grip and pull of strip 1 being drawn over its substantial contact with roll 8. This is in part a matter of choice and in part a matter of the nature of strip 1. The objective is such drive that the linear travel of strip 1 and of the periphery of roll 8 in contact therewith are precisely the same in any given situation.

Strip 1 is to stop intermittently at a predetermined position 11. At this position an operation of one sort or another is performed on the stopped strip 1 by suitable known means depending on the purpose, for example exposure by photographic means 33. After this operation at station 11, strip 1 moves forward again to bring up the next portion to stopping position 11. This advances the first portion by a distance designated as X in the drawing, to some position 12. The extent of this advance X, or the location of position 12, may differ from one situation to another, so variation of position 12 is indicated by opposed arrows. In any event, a point on strip 1 first occupying position 11 will next occupy a particular position 12 exactly.

In this description and claims the extent that strip 1 moves forward each interval is termed the advance. The portion of

the advance occupied by a photographic exposure is termed a frame. Each frame normally is bounded by a margin at least at each end within the advance. If the advance is increased or decreased in given case, this change is termed an increment.

Certain features of the combination of parts in this invention fix the precision of stopping the advances of strip 1.

Peripheral cogs 27, as in wheel 26-27, are attached rigidly to metering roll 8. On movement to a predetermined extent, an appropriate cog 27 is brought to abut a rigid stop 28 at a fixed point. This necessarily halts the travel of roll 8 and of strip 1 exactly at the target position, for roll 8 and strip 1 in contact therewith move and stop together precisely. Subsequently, the cog is released and advance of strip 1 is resumed.

Travel of strip 1, to control this operation of stopping the advance, acts not only through cogs 27 but also through power means to bring the rigid stop 28 into proper position ahead of a cog 27.

The drawing shows rigid stop 28 as a pawl having arm 14 pivoted at a fixed point and rotatable into and out of engagement position with a cog 27. The pawl end opposite to face 28 is continually under pull of spring 25 directed to move the face 28 down in front of a cog 27. The same pawl end is subjected to opposing power by connection to electromagnet 24. In closed circuit the pull of the element 24 is sufficient to overcome spring 25 and raise and latch pawl face 28 from engagement with cog 27. In open circuit, electromagnet 24 is deenergized and releases the pawl to move into position under power of spring 25. The continual pull of pawl 28 aids in easing the release of pawl face 28 when power of electromagnet 24 is applied after a cog has been stopped. A jerky or kick type of release is less desirable.

A combined counter and variable switch 13 is operated by metering roll 8 to cause quick power control of electromagnet 24 in circuit 23 and, if desired, of motor 2. Circuit 23 and the circuit to motor 2 are part of a principal circuit 18.

Roll 8 drives counterswitch 13 by belt 21. This element 13 comprises a pair of rotatable hands 19 and 22. Hand 22 is settable to indicate a predetermined amount of travel or advance of strip 1 with roll 8 while hand 19 is moved along part 15 of circuit 18 between terminals 16-16' and 17. Hand 19 comes to open this circuit at terminal 16'. This opens the circuit of electromagnetic pawl latch 24, and, as shown in the drawing, of motor 2 also. Normally both hands 19 and 22 are set at the same point, from which hand 19 is moved over incremental points 20. Hand 22 is not a part of the circuit. When hand 19 opens the circuit at terminal 16', the circuit may be left open until 19 is returned later; or, hand 19 may be spring-biased to return at once to its setting, as indicated by opposed arrows in the drawing. In the latter case the circuit continues open automatically through a holding circuit indicated by numeral 32 in circuit 18 until manually or automatically closed. Both counterswitch 13 and holding circuit 32 are well-known types of themselves and need no further description.

To revert to cogs 27, corresponding faces are spaced apart a distance that is a desired discrete proportion of the strip advance. This bears a simple fractional relation to the circumference of roll 8, or the number of cogs on a given roll. For example, if there are 6 cogs 27 and the circumference of roll 8 is 12 inches, then each cog is spaced to correspond to 2 inches of travel of that circumference and also of strip 1. If the advance X of strip 1 each period is 4 inches then rotation of two cogs 27 and their spaces 26 past a given point fixes each 4-inch advance of strip 1. This is a precise position since each cog face to be engaged comes to abut pawl face 28 at a precisely fixed point.

An important consideration in determining the relationship of pawl face 28 and cog 27 is to provide that the face 28 makes contact at a point where the cog face is tangent to the circle of rotation of the pawl. That is, a radius from the fixed center of swing of pawl face 28 through the contact of the face meets the cog face 27 at right angles as indicated by dotted line 34. In this arrangement the pawl lifts up without binding when the

electromagnet 24 acts and on the other hand the pawl is not loose when holding a cog. This is important especially when the cogs are operated by motor 2 and slip clutch 31 so that power is exerted between cog 27 and pawl face 28. A binding against cog 27 tending to kick the cog would tend to slide strip 1 relatively to roll 8 rather than maintain desired fixed contact.

The drawing shows each of the equal spaces between adjacent cogs somewhat wider than the end of pawl 14. This permits the pawl to enter the space and be in position wherever it may in front of the appropriate cog and permits the oncoming cog to move more or less until stopped by abutting pawl face 28. This freedom of movement absorbs whatever erratic action there may be in the mechanisms; yet stopping the travel of strip 1 occurs exactly at the fixed meeting point of cog and pawl. The drawing shows the top surface of the cogs as flat, to permit limited travel of cog 27 and strip 1 even if the pawl happens to descend upon the top of the cog ahead of the selected one. In many cog and pawl arrangements the cogs are so close together or otherwise made that a pawl may engage one cog or another without certainty. In the present invention the pawl comes to abut only the intended cog as spaces 26 are relatively about as wide or wider than cogs 27 themselves.

It is clear that the number and strip coverage of cogs 27 may vary, depending on circumference of roll 8 and the desired advance X of strip 1. Also by changing the cog wheel 26-27 to another wheel having a different number of cogs, a different range of cog coverage of strip travel may be substituted. In any case, increments of strip advance correspond to a given cog spacing. If instead of the six cogs 27 shown in the drawing there were 24 cogs, for example, with the 12-inch circumference of roll 8, then each increment would be one-half inch. Each space 26 or each increment of strip 1 advance is a discrete proportion of the advance.

Selection of a desired number of increments or of strip advance in a given case is by setting indicator hand 22, if desired, and switch hand 19, on a chosen marker 20 for hand 19 to be moved the remaining distance to terminal 16'. The spacing of markers 20 is proportioned to the distance between cogs 27, as by arrangement of the switch drive from roll 8 such as shown in the drawing. Thus variable switch 19 is operative at different positions connected to release pawl 14 at corresponding different positions of advance of roll 8 and a cog 27 into pawl abutment position. Thus advance of strip 1 may be increased or decreased by the number of increments or cogs rotated before pawl 14 is dropped in front of a predetermined cog 27.

To afford delicate control of movement of strip 1, this apparatus preferably includes variable brakes and clutches. The drawing shows a variable clutch 29 on motor 2 to regulate belt pull. A slip-clutch 31 may apply to roll 8 if desired to minimize the shock of sudden stopping of cog wheel 26-27. A slight ten-

sion preferably is maintained by takeup roll 4 so as to keep strip 1 suitably taut at all times. Similarly supply roll 3 is served by adjustable brake 30 to aid in maintaining strip 1 suitably taut.

5 Those skilled in the art will now be able to provide equivalent elements to those shown in the drawing. For example instead of electric power and components, fluidic power may be equivalent for many uses of this invention. Also other changes and equivalent operations may be made within the 10 scope of the appended claims. In accordance with the Patent Statutes, a preferred embodiment and presently best mode of operation have now been set forth in this description of this invention.

What is claimed is:

15 1. In photocopying apparatus having means to advance a sensitized strip and means to maintain the strip under tension at a takeup roll, means to stop the strip advance intermittently and means to expose the stopped strip, the combination of stopping means comprising a metering roll positioned to have 20 its peripheral face in extensive, at least semicircular, adjustable contact with the advancing strip, means to adjust said strip contact, separate means to drive the roll connected to the roll and adjustable in conjunction with adjustment of the advancing strip to obtain linear advance of the roll peripheral face 25 and of the strip precisely the same, a series of cogs fixed to the side of the metering roll, a pawl mounted to be brought into position to abut a cog and thus stop the roll, the cogs having faces adapted to abut the pawl at fractional circumferential distances apart in discrete proportion to the strip advance, 30 means to latch the pawl out of cog abutment, means to move the pawl into said abutment position, and control means connected to the pawl latch means and to the metering roll and operative by the roll itself in its advance to release the pawl latch means at predetermined advance of the roll and enable 35 the aforesaid pawl-moving means to move the pawl into a corresponding roll-stopping abutment position, thereby stopping the roll and the strip advance.

2. Photocopying apparatus as claimed in claim 1 wherein the said means to move the pawl into cog abutment position is applied continually and the said control means comprises means to latch the pawl out of said abutment position and comprises electric circuit means including variable switch 40 means connected for operation by the roll itself in its advance to release said pawl latch means by predetermined advance of the roll to bring a cog and pawl into roll-stopping abutment position.

3. Photocopying apparatus as claimed in claim 1 wherein the said means to latch the pawl out of cog abutment is electromagnetic and the said control means comprises an electric circuit including both the latch means and a switch means 50 operative by the roll itself in its advance to release the latch means at predetermined advance of the roll.
